PROCESS FOR REFINING HYDROCARBONS.

Application filed March 2, 1923. Serial No. 622,386.

- This invention relates to the process of refining hydrocarbons and more particularly to the separation or fractionation of certain distillates without redistillation whereby we 5 can make a merchantable commercial gasoline complying with the specifications as to boiling points, etc., demanded by the trade, directly from the crude oil with one distillation.
- 10 We accomplish this object by distilling the oil and passing the distilled vapors to a dephlegmating tower or similar apparatus and we control the temperature of such tower by withdrawing from near the bottom such condensates as are formed therein, cool the same and return the cooled condensate to the tower where they are brought into contact with the distilled vapors, thus washing, scrubbing and condensing part of the vapors, allowing 15 other vapors to pass out of the tower or similar apparatus through a cooling apparatus where they are condensed.
- We may use a succession of stills and towers if desirable, maintaining each of the 20 towers at such temperatures as may be desired by regulating the speed of the pumps which circulate the liquefied portion of the oil through the towers and by means of the circulating liquid we may condense and remove from the mixed vapors the higher boiling point oils and allow the lower boiling point oils to pass on as a residual vapor, condense the same and mix them as desired to produce a finished gasoline directly from 25 the oil, eliminating the usual steam distilling process.
- These results may be obtained by an apparatus shown and described in the single figure of drawings accompanying this application 30 in which:
- 1 represents a still in which for example oil is charged through a charging line 2 from a source of supply not shown, which is heated by heat applied through fire box 3 sufficiently 35 to cause vapors to rise and pass off through dome 4, vapor line 5, into tower 6, up through a baffling medium which for convenience is shown on the drawing as baffles 7, out through vapor line 8, through condenser coil 9 where the vapors are condensed, coil 9 being situated in cooler box 10 and submerged in cold water supplied through line 11 from a source of 40 supply not shown. The condensate from coil 9 passes through look box 12 and rundown line 13 into receiving tank 14.
- A still of this type can be run separately, charged with oil from a source of supply in single batches, or semi-continuously, allowing the residuum to accumulate in still until fully charged as the vapors are driven off, in 45 either of which cases when run is complete residuum is withdrawn from still 1 through dump line 16, pipe 42, valve and line 43 to cooler and receiving tank not shown; or continuously from a source of supply, allowing 50 the residuum from which the vapors are being continuously distilled off as above described to overflow from still 1 through overflow line 15 into still 1-A, where the process of distillation is continued and more vapors 55 are continuously distilled off through dome 4-A, vapor line 5-A, tower 6-A up through a baffling medium which for convenience is shown on drawing as baffles 7-A, out through vapor line 8-A, through coil 9-A where vapors are condensed, coil 9-A being situated in cooler box 10-A and submerged in cold water supplied through line 11-A from a source of supply not shown. The condensate from coil 9-A passes through 60 look box 12-A and rundown line 13-A into receiving tank 14-A. The residuum from which the vapor is being continuously distilled is withdrawn continuously from still 1-A through line 16-A, pipe 42-A, valve 65 and line 43-A, to cooler and receiving tank not shown.
- While only two stills are shown and described in this drawing and specifications, it is to be understood that any number of 70 stills can be similarly arranged in series and run continuously, taking off any quantity of vapors in such fractions as desired.
- While such arrangements are not shown, 75 stills may be equipped or not as desired with steam pipes for steam distillation. It is also to be understood that the stills may be heated by fire as described, or by steam or any other means for heating or means to induce vaporization.
- It is also to be understood that the oil may 80 be distilled for any purpose and the use of this method is applicable and beneficial wherever it is necessary or desirable to use dephleg-

mating towers or reflux condensers in any form, and an object of the invention is to control the temperature of same when applied to and used in connection with dephlegmating 5 towers and fractionating towers already in general use and common practice in destructive distillation or cracking stills, as well as in the production of wax distillate, where the crystalline structure is formed by a certain 10 desired amount of destructive distillation, generally known as "cracking," by refluxing the condensate from a tower back to the still from which it came.

It is further to be understood that the above 15 applies to steam stills, pressure still or vacuum stills, or a vaporization chamber in connection with a pipe still, or any other type of still, whether it be vacuum or pressure, where the reflux condensates from the tower 20 may be returned or directed to a zone where it is subjected to a further distillation treatment.

It is to be understood that this method is 25 for the purpose of controlling the temperature of any dephlegmating tower, fractionating tower or condensing apparatus of any kind.

For the purpose of describing and giving 30 a clear understanding of the operation of the method which comprises our new and useful discovery, we have given the above outline of a generally accepted and well known method of distillation, and the method of our process as particularly applied to same is described below. It is to be understood, however, 35 that this description is to illustrate and describe the method employed and is not necessarily confined thereto. We will therefore consider that continuous distillation as heretofore described is in progress and that mixed vapors in accordance with the general and well known practice are coming off and passing through the apparatus as described.

The oil in still 1 is heated to a temperature 40 of approximately 450° F. The vapors passing off through the tower and condensing apparatus are condensed and pass through look box 12 at a gravity of about 52° Baumé. At the same time the oil in still 1—A will be 45 heated to a temperature of about 520° F., and the vapors passing off through the tower and condensing apparatus are condensed and pass through look box 12—A at a gravity of about 46° Baumé. This is in accordance 50 with the general and well known practice. The stocks being thus produced when blended and mixed in the proportions as distilled make what is known in the art as crude naphtha, and in order to make 55 commercial gasoline that is water white and to meet the specifications as to boiling points, etc., demanded by the trade it is necessary to redistill this stock in order to properly fractionate and separate the lighter fractions 60 from the heavier fractions which constitute

the crude naphtha which is the result of the total condensed mixed vapors distilled from the two stills as described.

By the method of fractionating which we employ we are enabled to eliminate this redistillation and make a merchantable commercial gasoline of the specifications as to boiling points, etc., demanded by the trade direct from the oil with one distillation, which is accomplished as follows:

During distillation vapors passing from still 1 through dome 4 and vapor line 5 into tower 6 and upward through baffles 7 are naturally cooled by expansion therein and contact with the baffles while passing through the tower, and a certain amount of condensation takes place within the tower, which condensate collects upon the baffles and refluxes or flows backward to the bottom of the tower 6, filling outlet pipe 17, running by gravity 80 through cooling pipe 18 situated in cooler jacket 19 filled with cold water through inlet pipe 20 from a source of supply not shown. This cooler jacket if occasion requires may be used as a heating jacket instead of a cooler 85 by the admission of steam through pipe 21 from a source of steam supply not shown instead of water when used as a cooler. This 90 may be necessary in circulating wax distillate when running for same. The cooled condensate flows by gravity from cooling pipe 18 through pipe 22 and valve 38, pipe 39 and valve 40, to pump 23, induced by suction thereof. The speed of pump 23 is regulated 95 by steam valve and line 24 from a source of steam supply not shown. Pump 23 discharges this condensate through valve 34 and line 25 into the upper portion of tower 6, and it flows by gravity down over baffles 7, coming into intimate contact with the 100 mixed vapors passing upward through the tower and baffles, falling to the bottom of the tower, from whence it is circulated continuously through outlet pipe 17, cooling pipe 18, pipe 22 and valve 38, pipe 39 and valve 40, 105 with pump 23, valves 28 and 41 being closed.

It will be obvious that the quantity of 110 cooled condensate entering tower 6, regulated by the speed of the pump, will positively control the temperature of the vapors passing upward through the tower to any degree desired. The cooling effect will condense and remove from the mixed vapors the higher 115 boiling point hydrocarbons and allow the lower boiling point hydrocarbons to pass on as a residual vapor. The liquid circulating condensate coming into intimate contact with the mixed vapors will also wash or scrub the vapors and remove and combine with substantially all like hydrocarbons present therein. The condensates or higher boiling point fractions of the mixed vapors extracted in the tower by the like circulating condensates and mixed therewith flow to the bottom of tower 6, and the excess amount accumulated or 120

extracted by the like circulating medium not used and contained in the circulating system overflow from the bottom of tower 6 through valve 27, pipe 26 and valve 31, valve 32 being 5 closed, and refluxes or flows by gravity back to still 1 from which the vapors originally came. It is obvious that the circulating system while operating will always contain the same quantity of distillate and the excess 10 condensate will overflow and escape through any opening provided.

The residual vapors after having been scrubbed as described pass upward from tower 6 through vapor line 8 into condenser coil 9 15 and are condensed. The condensate flows from coil 9 through look box 12 and through run-down line 13 into receiving tank 14. Samples are taken from the stream of condensate passing through look box 12 at regular intervals, 20 and the speed of pump 23 is so regulated by steam valve 24 that the gravity of the distillate flowing through look box 12 will be 60° Beaumé, or any desired gravity for a finished product. The gravity of this stream can be 25 and is absolutely controlled by the speed of the pump, which regulates the quantity of cooled condensate being circulated through the tower 6, which fractionally separates from the mixed oil vapors coming from still 30 1 while passing through tower 6 the heavy fractions having substantially the same composition as the circulating hydrocarbons being circulated and returns or refluxes all of the excess separated and condensed like 35 hydrocarbons not used and contained in the circulating system to still 1, thereby controlling the gravity of the distillate flowing through look box 12, which is the condensed residual vapors or light fractions of the 40 mixed vapors from which the heavy fractions have been separated as described. The still is maintained at approximately the same temperature, viz., 450° F.

As previously described, it will be noted 45 that the gravity of the stream before starting to circulate the condensate through the tower was 52° Beaumé in look box 12, whereas after circulating the gravity of this condensate will be approximately 60° Beaumé.

The gravity of the distillate from this still 50 can be positively regulated within the reasonable limits of the natural distillate content of the oil under distillation.

The residuum overflowing from still 1 through overflow pipe 15 into still 1—A is 55 heated to and maintained at a temperature of approximately 520° F., distilling off the vapors through dome 4—A, vapor line 5—A, into tower 6—A, passing upward through baffles 7—A, out through vapor line 8—A to condenser coil 9—A, where the vapors are 60 condensed, coil 9—A being situated in cooler box 10—A submerged in water from pipe 11—A from a source of supply not shown.

65 The condensate from condenser coil 9—A

passes through look box 12—A, pipe 13—A to receiving tank 14—A. The gravity of the condensate passing through look box 12—A will be approximately 46° Beaumé.

With still 1—A running in a continuous 70 battery with still 1 as above described, circulating equipment supplied and controlled by pump 23—A is manipulated in a like manner as described in the manipulation of pump 23, so as to control the gravity of distillate and 75 raise it from 46° to 56° Beaumé in like manner as in the manipulation of pump 23 and apparatus as previously described in connection with still 1. Inasmuch as the manipulation and operation of the control of the gravity of the distillate produced from still 1—A by the pump 23—A and the fractionating apparatus therewith connected is the same as described in connection with still 1; the details of this operation and manipulation are omitted for brevity.

The distillate thus produced with the aid of the fractionating apparatus as described, when blended in the proportions as produced, makes a commercial water white merchantable gasoline of the specifications as to boiling points, etc., as demanded by the trade. This gasoline can be made to any desired specifications as to boiling points, gravity, etc., within the reasonable limits of the gasoline content 95 of the oil under distillation by manipulation of the circulating distillate within the apparatus.

It will be noted from the above that by 100 this method we have produced a finished gasoline directly from the oil, eliminating the usual steam distilling process.

It is to be understood that the above method employed as described can be varied in substantially every detail in the steps of the 105 process; for example, if it is not desired to reflux the excess condensate not contained and used in the circulating apparatus, the valves 27/27—A may be closed on reflux pipes 26/26—A and valves 28/28—A may be 110 opened so that the excess condensates not used in circulating will overflow by gravity through pipes 29/29—A to receiving tanks 30/30—A. In this manner the mixed vapors coming from the stills can be fractionated or 115 separated into two component parts. The properties of these two component parts may be varied to any degree within the reasonable limits of the natural content of the mixed vapors.

It is further to be understood that by the addition of more towers to each still, fully equipped with pump and circulating apparatus, arranged in series in the vapor lines 5 and 8, that the mixed vapors may be fractionated into any reasonable number of fractions consistent with the total content of the mixed vapors under distillation.

It is further to be understood that the excess condensate not contained and used in the 130

circulating apparatus may be disposed of in various ways; for example, it may be refluxed or allowed to flow by gravity from tower 6 to still 1—A by closing valves 28, 38 and 31 on reflux pipe 26 and opening valve 27 on reflux pipe 26, and valves 32/32—A on cross-over reflux line 33, and opening valve 31—A on reflux line 26—A.

It is to be understood that this operation 10 may be reversed as regards still 1—A and its apparatus and still 1 and its apparatus; furthermore, if the lines of the apparatus as delineated on the drawing are followed it will be noted that the excess condensate not 15 contained and used in the circulating apparatus may be disposed of in various ways as described hereafter: The excess condensate may be allowed to flow back again by gravity from the bottom of tower 6 to the 20 still 1 from which it was received in vapor phase, this refluxing being accomplished by flowing through the line 26, valves 27 and 31 being open and valve 32 in branch line 33 being closed. In the same way as above 25 the excess condensate of tower 6—A may be allowed to flow back to still 1—A.

The excess condensate may be allowed to flow from tower 6 to still 1—A where a higher temperature is maintained than in still 1, this 30 refluxing occurring through line 26, branch line 33 and line 26—A, valves 27, 32, 32—A and 31—A being open and valve 31 being closed, while the reflux of excess condensate of tower 6—A may be allowed to flow also 35 to still 1—A through line 26—A, valve 27—A being open depending upon the stock handled and the products desired.

The excess condensate of tower 6 may be allowed to flow for a part back to still 1 and 40 for the remaining part back to still 1—A respectively through lines 26, 33 and 26—A, valves 27, 31, 32, 32—A and 31—A being open while valve 27—A can be open or closed depending whether the reflux of tower 6—A 45 is run to storage tank 30—A or also back to the still 1—A.

The excess condensate of tower 6 may be allowed to flow directly to a storage tank 30 through line 17, 18 and 29, valve 28 being 50 open and valve 27 in line 26 being closed. In the same way the excess condensate of tower 6—A may be run down to storage tank 30—A.

It is further understood that the condensates from towers 6 and 6—A may be directed or discharged from pumps 23 and 23—A from one part of the apparatus to any other part of the apparatus of the various stills and units thereof. This may be seen 55 by following the lines as delineated in the drawing of the apparatus. It is to be understood, for example, that by closing valve 34 on line 25 and opening valves 35 and 35—A on cross-over line 36, pump 23 may discharge 60 condensate from bottom of tower 6 through

open valve 34—A and line 25—A to the upper portion of tower 6—A. Likewise, the position of the towers and functions of the pumps may be reversed in the operation. Likewise, the contents and the receipts into 70 and out of tanks 30 and 30—A can be shifted to and from the different parts and units of the apparatus and used within the different parts of the different circulating systems.

The same purpose may be accomplished in 75 the fractionating apparatus by using the residual oil from stills 1 and 1—A in pumps 23 and 23—A as a circulating medium through the towers 6 and 6—A in lieu of the condensate from said towers as heretofore 80 described. The residual oil, for example, will be used in the following described manner:

Suction will be taken from stills 1 and 1—A through dump lines 16/16—A, pipe 85 42/42—A and cooler pipes 37/37—A with pumps 23/23—A, discharging through lines 25/25—A to the upper portion of towers 6/6—A, where the cooled residuum flows by gravity down over baffles 7/7—A, coming 90 into intimate contact with the mixed vapors passing upward through the tower and baffles, to the bottom of the tower, from whence it is passed back through valves 27/27—A, lines 26/26—A and valves 31/31—A, valves 95 32/32—A being closed, to the still from which it came, mixed with the resultant condensate from the towers, valves 28/28—A and 38/38—A being closed.

We claim:

100

1. The process of fractionally separating mixed hydrocarbons having different boiling points which consists in vaporizing the hydrocarbons and passing the vapors to the lower part of a fractionating tower to condense the higher boiling point fractions as the vapors rise in the tower, withdrawing from an outlet at the bottom of the fractionating tower some of the liquid hydrocarbons condensed ther in and circulating the condensates back to the upper part of the tower and allowing them to flow back down through the tower, thus bringing them into intimate contact with the mixed vapors passing up through said tower and liquefying 110 and separating from the mixed vapors as they pass up through the tower, the fractions having substantially the same composition as the circulated hydrocarbons, and refluxing the resultant excess separated and condensed hydrocarbons not used in circulation back to the still from which the mixed oil vapors were obtained.

115

2. The process of fractionally separating mixed hydrocarbons having different boiling points which consists in vaporizing the hydrocarbons and passing the vapors to the lower part of a fractionating tower to condense the higher boiling point fractions as the vapors rise in the tower, withdrawing 120 125 130

from an outlet at the bottom of the fractionating tower some of the liquid hydrocarbons condensed therein and circulating them back to the upper part of the tower and allowing them to flow back down through the tower, thus bringing them into intimate contact with the mixed vapors passing up through said tower and liquefying and separating from the mixed vapors as they pass up through the tower, the fractions having substantially the same composition as the circulated hydrocarbons and refluxing apart of the excess separated condensed hydrocarbons not used in circulation back to the still from which the mixed oil vapors were obtained and the remaining part of the excess separated condensed hydrocarbons back to a successive still where a higher temperature is maintained than in the still from which the vapors were obtained.

3. The process of fractionally separating mixed hydrocarbons having different boiling points which consists in vaporizing the hydrocarbons and passing them to the bottom of a fractionating tower and allowing them to rise through the tower to condense some of the vapors, circulating from an outlet near the bottom of the fractionating tower through the upper part of said tower, liquid hydrocarbons condensed therein and bringing them into intimate contact with the mixed oil vapors passing through said tower, thus separating from the vapors the fractions having substantially the same composition as the circulated hydrocarbons and refluxing some of the resultant excess separated and condensed hydrocarbons not used in circulation back to the still from which the mixed oil vapors were obtained, passing some of the condensed hydrocarbons to a further fractionation by the same process in a second fractionating apparatus operated at a different temperature and separating and condensing the residual vapors from both apparatuses.

4. The process of fractionally separating hydrocarbons having different boiling points, which consists in vaporizing the hydrocarbons and passing them to the bottom of a fractionating tower and allowing them to rise through the tower, circulating from an outlet near the bottom of the fractionating tower through the upper part of said tower liquid hydrocarbons condensed therein and bringing them into intimate contact with the mixed hydrocarbon oil vapors passing through said tower, thus separating from the vapors the fractions having substantially the same composition as the circulated hydrocarbons, refluxing some of the resultant excess separated and condensed hydrocarbons not used in circulation back to the still from which the mixed hydrocarbon oil vapors were obtained, passing some of the condensed hydrocarbons to a further fractionation by the same process in a second fractionating apparatus operated

at a different temperature and separately condensing the residual vapors from both apparatuses, then removing from both apparatuses the resultant excess separated and condensed hydrocarbons not used in circulation. 70

5. The process of fractionally separating mixed hydrocarbons of different boiling points which consists in vaporizing the hydrocarbons and passing them to the bottom of a fractionating tower, to condense the higher boiling point fractions as the vapors rise through the tower, withdrawing from an outlet at the bottom of the fractionating tower some of the liquid hydrocarbons condensed therein and returning the same to the still, redistilling them and passing them a second time to the tower, condensing some of the higher boiling point fractions in the tower and then passing some of the condensates to a second still and redistilling them and removing the resultant excess separated and condensed hydrocarbons from the still and separately condensing the vapors finally issued from both stills. 85

6. The process of fractionating mixed hydrocarbons which are normally liquefied at atmospheric temperature, but have different boiling points, comprising vaporizing the more volatile fractions and passing them to the bottom of a fractionating tower and allowing them to rise therethrough, leaving the residual liquid fractions in the still for subsequent disposal, condensing some of the higher boiling point portions of said hydrocarbon vapors as they rise in the tower and circulating a portion of the condensed hydrocarbon vapors withdrawn from the bottom of the tower through a cooler back to the top of the tower and bringing this cooled condensate into intimate contact with the rising vapors, simultaneously regulating the temperature of said circulating liquid condensate by regulating the amount of condensate supplied to the tower, and conducting the excess of the withdrawn condensate, 100 not remaining in circulation, back to the still from which it came. 105

7. The process of fractionating mixed hydrocarbons which are normally liquefied at atmospheric temperature, but have different boiling points, comprising vaporizing the more volatile fractions and passing them to the bottom of a fractionating tower and allowing them to rise therethrough, leaving the residual liquid fractions in the still for 120 subsequent disposal, condensing some of the higher boiling point portions of said hydrocarbon vapors as they rise in the tower and circulating a portion of the condensed hydrocarbon vapors withdrawn from the bottom of the tower through a cooler back to the top of the tower and bringing this cooled condensate into intimate contact with the rising vapors, simultaneously regulating the temperature of said circulating liquid con- 125

- densate by regulating the amount of condensate supplied to the tower, conducting a part of the excess of the withdrawn condensate, not remaining in circulation back to the still from which it came and the remaining part of the excess back to a successive still, where a higher temperature is maintained,

than in the still, from which the vapors were obtained.

In testimony whereof we hereunto affix 10 our signatures.

JOHN C. BLACK.
JAMES W. WEIR.
